(57) **CLAIM**

The ornamental design for a paintbrush holder, as shown and described.

DESCRIPTION

FIG. 1 is a top side perspective view for a paintbrush holder showing my new design;

FIG. 2 is a top side view thereof;

FIG. 3 is a bottom side view thereof;

FIG. 4 is a rear side view

FIG. 5 is a front side view thereof;

FIG. 6 is a left side view, the right side view being a mirror image thereof;

FIG. 7 is a bottom side perspective view thereof;

FIG. 8 is a left sectional view taken along lines **8-8** from FIG. 3 thereof; and,

FIG. 9 is a top side perspective view thereof shown in an environment of use.

The broken lines in FIG. 9 depict environmental subject matter only and form no part of the claimed design.
